UNITED STATES PATENT OFFICE.

GEORGE M. PORTEOUS AND FREDERICK S. MILLER, OF CHICAGO, ILLINOIS.

DESIGN FOR A PHOTOGRAPH-EXHIBITOR STAND.

SPECIFICATION forming part of Design No. 18,870, dated January 15, 1889.

Application filed November 5, 1888. Serial No. 290,064. Term of patent 7 years.

To all whom it may concern:

Be it known that we, GEORGE M. PORTEOUS, a citizen of the United States, and FREDERICK S. MILLER, a subject of the Queen of Great Britain, both residing at Chicago, in the county of Cook and State of Illinois, have invented and produced a new and original Design for a Photograph-Exhibitor Stand, of which the following is a specification, reference being had to the accompanying drawing, forming part thereof.

In said drawing, the figure represents in elevation a photograph-exhibitor having a stand embodying our design.

The leading feature of our design consists in the stand having a pair of curved arms extending upwardly from its top portion and pendants diverging downwardly from a point below said curved arms, substantially as herein shown and set forth.

In said drawing, B indicates the stand, having its top portion formed by a pair of curved upwardly-extending arms, b, which can be either plain or ornamented, as may be desired.

The pendants b^2 drop from a point below the arms b and diverge downwardly. The lower ends of the pendants may, however, and herein are, turned toward one another, so as to avoid a too abrupt termination. Said pendants can be variously ornamented without departing from the spirit and leading feature of our design, it being seen that, since the curved arms b diverge upwardly, the downward divergence of the pendants serves to balance the whole in appearance and also to harmonize with the said curved arms.

What we claim is—

A design for a photograph-exhibitor stand, consisting of the stand having upwardly-extending curved arms b and pendants b^2 , which diverge downwardly from a point below said curved arms, substantially as shown and described.

GEORGE M. PORTEOUS.
FREDERICK S. MILLER.
